UNITED STATES PATENT OFFICE.

GEORGE T. PINE, OF SCOTT DEPOT, WEST VIRGINIA.

ACCOUNT-KEEPER.

No. 893,366.

Specification of Letters Patent. Patented July 14, 1908.

Application filed November 30, 1907. Serial No. 404,565.

To all whom it may concern:

Be it known that I, GEORGE T. PINE, a citizen of the United States of America, and resident of Scott Depot, county of Putnam, 5 State of West Virginia, have invented certain new and useful Improvements in Account-Keepers, of which the following is a full and clear specification, reference being had to the accompanying drawings, in 10 which—

Figure 1 is a perspective view of my book-like account-holder; and Fig. 2 is a detail transverse sectional view of one of the frame-like leaves.

15 The object of this invention is to provide means whereby ordinary store accounts may be kept without employing the usual account books thereby resulting in great saving of expense in the matter of books and also 20 the saving in labor, as more fully hereinafter set forth.

The invention has reference especially to that class of easy account keepers covered by my former patent No. 842,421, dated 25 January 29, 1907, in which a series of leaf-like frames are hinged together in the manner of a book, each frame having its opposite faces divided by longitudinal strips to form vertical channels or spaces for the reception 30 of clamps for holding the pads or piles of account slips. My present improvements are designed to simplify this book-like structure and to adapt it for use without a cabinet such as shown in my former patent.

35 In the drawing, *a* designates the front cover of the book, *b* the rear cover, and *c* the flexible cloth or other back piece to which the series of leaf-like frames *d* are glued or otherwise fastened.

40 Each leaf consists of a marginal frame, preferably of wood, and a main or body plate of sheet-metal *e* whose edges are fitted in grooves around the inner wall of the frame. The longitudinal ribs on the plate *e* are 45 formed by folding the metal on longitudinal lines and closing the folded parts to form oppositely projecting ribs *f* which form the longitudinal channels or spaces for the reception of the account slips. Any number 50 of slip-holding clamps *g* may be employed in each channel, each of these clamps being fastened directly to the sheet-metal dia-

phragm. Each one of these clamps will be numbered for convenience in indexing, as shown in Fig. 1. In Fig. 1 the front page of 55 the first frame is shown and this is provided with nine account holders, so that with the same number on the opposite side of this frame the first leaf or frame will provide for eighteen accounts at least. The opposite 60 sides of the frames are preferably provided at the upper right-hand corner with a page number, so that with this page number and the individual account numbers adjacent to each clamp it will be a simple matter to provide a ready index. I prefer employing the inside face of the front cover for holding the index, as shown in Fig. 1, this index consisting of suitably ruled paper pasted on the cover. The inner face of the back cover 70 may also be used for an index if desired.

It will be observed that my improved cabinet is a complete account-keeping outfit and its great advantage is that it is readily portable and may be used on any 75 desk or table that may be convenient and may be put away in the safe for safe-keeping over night. The peculiar manner of forming the oppositely projecting ribs by folding the metal in opposite directions and closing the 80 folds gives great strength and durability to the leaves and solidly braces the frames.

Having thus fully described my invention, what I claim as new and desire to secure by 85 Letters Patent, is:—

In a device of the class set forth, consisting of a flexible back, a pair of covers connected thereto, and a series of leaves attached to the flexible back, each leaf consisting of a rectangular frame inclosing a metal sheet whose 90 edges engage the bars of the frame, said sheet being provided with upstanding ribs on its opposite faces formed by folding the metal in opposite directions and closing the 95 folds, and a series of account-slip-clamping devices on the sheet-metal plate between the ribs.

In testimony whereof I hereunto affix my signature in the presence of two witnesses this 29 day of Nov. 1907.

GEORGE T. PINE.
